UNITED STATES PATENT OFFICE.

CHARLES W. BECK, OF ROCKVILLE CENTER, NEW YORK, ASSIGNOR, BY MESNE ASSIGNMENTS, TO THE BECK-FROST CORPORATION, OF DETROIT, MICHIGAN, A CORPORATION OF MICHIGAN.

CARBURETER.

1,211,386.

Specification of Letters Patent.

Patented Jan. 9, 1917.

Application filed October 19, 1911. Serial No. 655,453.

To all whom it may concern:

Be it known that I, CHARLES W. BECK, a citizen of the United States, and resident of Rockville Center, county of Nassau, and 5 State of New York, have invented certain new and useful Improvements in Carbureters, of which the following is a specification.

One of the main objects of this invention 10 is to provide means in a carbureter for completely breaking up the minute globules of gasolene before they enter the intake of the engine, so that the gasolene will be thoroughly vaporized and incorporated with 15 the air during all ordinary changes in temperature. The advantage of producing a mixture in which the gasolene is completely vaporized is manifest.

Another object of the invention is to provide 20 a power-driven means by which any minute globules of gasolene drawn toward the engine intake will be broken up and completely vaporized.

Another object of the invention is to provide 25 improved means for controlling the air inlet into the carbureting chamber.

Another object of the invention is to provide 30 means for insuring the delivery of mixture in equal quantities to all of the cylinders, whether or not the suction or compression of said cylinders are equally efficient. That is to say, with my invention a cylinder having a worn piston or inaccurately fitting piston rings will be supplied 35 with the proper amount of mixture and with a like amount of mixture as a cylinder having a properly fitting piston.

Another object of the invention is to provide 40 means whereby any gasolene which may fall to the bottom of the carbureting chamber will be caught by an absorbent material and then vaporized.

Another object of the invention is to insure 45 a proper supply of air to the carbureting chamber, said supply of air being varied according to the speed of the engine.

A further object of the invention is to provide 50 means whereby the air inlet to the carbureting chamber may be somewhat obstructed when the engine throttle is fully open, said means being adjustable to vary the relative positions of the air intake control and the throttle valve so that the said air intake may be fully opened when the

throttle is open or may be somewhat obstructed when the throttle is fully open. The object of this form of air control is obvious, it being well known that when the throttle is open and it is desired to start the engine the air intake to the carbureting 60 chamber is desirably obstructed; but when the engine is running on full power it is desirable that the air intake into the carbureting chamber shall be unobstructed.

There are other objects and advantages 65 of the invention which will more fully hereinafter appear.

In the drawings Figure 1 is a vertical, 70 central, sectional view of the carbureter; and Fig. 2 a plan view thereof.

Referring to the various parts by numerals, 1 designates a float chamber which may be of any suitable construction and which contains the float valve 2, said float valve regulating the intake of gasolene into 75 said chamber in the usual manner. The level of liquid in the float chamber may be regulated by any of the suitable mechanisms used for that purpose. This chamber is provided with the usual spring-controlled 80 plunger 3 and the lever 4 for operating it, said plunger being designed to depress the float to permit gasolene to flow into the said chamber when priming or charging the carbureter chamber. Communicating with 85 the side of the float chamber in the usual manner is a pipe 5, said pipe being located a suitable distance above the bottom of the carbureting chamber to insure the proper depth of gasolene in the float chamber. 90 This pipe is formed with an outlet port 6 which communicates with a downwardly extending discharge port 7. The outlet port is controlled by the usual carbureter needle valve 8.

Secured to the pipe 5 and depending therefrom is an annular casing 9 which forms a carbureting chamber 10, the discharge port 7 being arranged in the center of said carbureting chamber at the upper end thereof. 100 Extending upwardly from said pipe and from the upper end of the carbureting chamber is a circular casing 11 which forms a mixing chamber whose lower end is in open communication with the carbureting chamber. In the mixing chamber is an exhaust wheel or blower 12 mounted upon shaft 13 whose outer end is connected by a flexible

shaft 14 to any suitable driving part operated by the engine. This mixing or exhaust wheel is formed with transversely extending curved blades 15 which are disposed between 5 two side rings 16. These blades are cup-shaped in transverse section, as shown clearly in Fig. 1, and the exhaust wheel rotates in the direction indicated by the arrow in said figure. It is manifest that as this 10 exhaust wheel is rotated it will draw air from the carbureting chamber at such a speed as to lift minute globules of gasoline and draw them into contact with said blades. As the blades will rotate at a high speed the 15 said minute globules of gasoline will be thoroughly broken up and dissipated by the action of the blades. This is of great importance for the reason that it is injurious to have the gasoline passing into the engine 20 cylinder in a badly, or partly vaporized condition and insufficiently mixed with the air.

The rapidly rotating exhaust wheel or blower will vary its speed in accordance with the speed of the engine so that the air supply, or the air drawn into the vaporizing chamber will be proportioned to the speed of the engine. The action of this suction or exhaust wheel is to materially assist in supplying air to the vaporizing chamber and in 25 forcing the mixture into the engine cylinders. It is manifest that the rapid rotation of this wheel will force a supply of mixture into the engine cylinders so that a cylinder provided with a badly fitting piston or badly fitting piston rings will be supplied with mixture practically to the same extent as a cylinder having a well fitting piston.

Connected to the side of the mixing chamber and in communication therewith is the engine intake pipe 17, so that the blades of the mixing or exhaust wheel will draw air up through the carbureting chamber and deliver it into the intake of the engine. It is 40 manifest that when the engine is running at high speed and the gasoline charge drops from the discharge opening in pipe 5 the uprush of air induced by the rapidly rotating exhaust and mixing wheel, and the suction 45 of the engine, will cause the unvaporized particles of gasoline to rush upwardly and bring them into violent contact with the blades of the revolving wheel. It is manifest that the continued rotation of the exhaust wheel will materially add to the speed 50 and volume of the upward currents of air through the carbureting chamber and also that its rotation will aid materially in vaporizing the gasoline. The violent motion of 55 the air and of the gasoline particles caused by the rotating exhaust wheel will rapidly vaporize the gasoline and thoroughly mix the vapor with the air before the mixture is delivered or permitted to flow into the intake 60 in response to the suction of the engine.

In the lower end of the carbureting chamber is arranged a horizontal piston 18 which comprises a ring 19 supported by spider arms from a hub 20. Stretched over the ring and carried thereby is a disk 20^a of felt or other suitable absorbent, pervious material, said material being secured to the outer surface of the ring and forming a yielding packing between the ring and the interior surface of the carbureting chamber. The 70 lower end of the casing forming the carbureting chamber is cylindrical in cross section in order to form a cylindrical chamber in which the piston may be reciprocated, as will be more fully hereinafter set forth. It will, of course, be understood that the felt or other absorbent material may be secured to the piston in any suitable manner. The purpose of using absorbent and pervious material across the 75 ring piston is to permit air to be drawn up through said piston when the piston is within the cylindrical part of the carbureting chamber, as will be more fully hereinafter set forth. The piston is supported upon the 80 upper end of a vertically reciprocating piston stem 21, the lower end of said stem being guided in a hub 22 carried by a depending spider frame 23 secured to the lower end of the casing forming the carbureting chamber. The 85 lower edge of the cylindrical part of the carbureting chamber is on an angle oblique to the vertical central line of said chamber, as shown clearly in Fig. 1, so that as the 90 piston 18 is lowered it progressively opens the lower end of said chamber to the atmosphere; and as it is raised into said chamber it progressively cuts off the free communication 95 of said chamber with the atmosphere, said chamber being in full open communication only when said piston is in its lowest 100 position.

It is manifest that when starting the engine, or at any time during its operation, if any gasoline reaches the piston it will be 105 absorbed by the piston covering and will then be taken up by the air which is drawn upwardly through the piston, and that there will be no accumulation of free gasoline within the carbureting chamber. It is also 110 clear that by varying the position of the piston in the carbureting chamber the amount of air passing freely into said chamber without being forced to pass through the piston may be varied.

In the engine intake is arranged the usual throttle valve 24 which is connected by rod 25 to any suitable form of throttle valve controlling means. Connected to the lower end of the piston stem 21 is a controlling 115 lever 26. The end of this lever is connected to the throttle valve by means of link 27 so that the piston will be moved simultaneously with the movement of the throttle valve. In the ordinary operation of the engine the 120

parts will be arranged as shown in Fig. 1, the piston being lowered when the throttle valve is opened, and being raised into the carbureting chamber when the throttle valve 5 is closed. When starting the engine, however, it is desirable that the piston be within in the carbureting chamber when the throttle is in its open position so that all air passing into the carbureting chamber will be drawn through the piston, thereby producing 10 a mixture rich in gasoline vapors. In order to provide for this arrangement of the piston and throttle valve the connecting link 27 is divided and the two parts connected together by means of a cam connecting device 28. This device is pivoted to one member of the link and is provided with a cam slot 29 in which the other member of the link is pivoted. By arranging the cam as 15 shown in Fig. 1 the link is shortened, but by throwing said cam upwardly it is manifest that the link will be extended. A spring 30 is connected to the cam and to one member of the link, and is so arranged that it 20 will hold the cam in either its upper or its lower position. The connection between said spring and the cam is so arranged that when the cam is in its upper position the tension of said spring is on one side of the center line between the two pivotal points of the link members, said tension holding the cam in its adjusted position; and when it is 25 in its lower position said spring connection is on the opposite side of the center line between the two pivotal points of the link 30 members and holds said cam in its said lower position. Of course, any suitable means may be provided for lengthening and shortening the link, the device shown being used merely 35 by way of illustration and as a simple means for illustrating this feature of the invention. It is manifest that when the throttle valve is opened in starting the engine it will only be necessary to swing the cam 28 to its 40 upper position to extend the link and thereby throw downwardly the outer end of the piston controlling lever. This will force the piston upwardly into the carbureting chamber and prevent the free passage of 45 air into said chamber. When the engine is running it will only be necessary to throw down the cam 28 in order to restore the piston to its normal position with relation to the throttle valve. It will, of course, be understood that any suitable means may be 50 provided for varying the relative positions of the throttle valve and the piston in starting the engine and when the engine is running and by that means varying the mixture of air and gasoline vapor delivered to 55 the engine intake. It will also be understood that the form of the lower end of the carbureting chamber may be varied as desired in order to vary the free intake of air 60 into the carbureting chamber by raising and 65

lowering the controlling piston, the means shown being one of many forms of devices which may be employed for that purpose.

From the foregoing it is manifest that by providing means for mechanically driving 70 the suction wheel at a high speed the gasoline delivered from the discharge outlet of the gasoline pipe will not reach the absorbent piston but will be taken up by the upwardly rushing air, and if not completely 75 vaporized before it reaches said wheel the unvaporized globules or portions of the gasoline will be struck by the rapidly moving vanes of the suction wheel and thoroughly broken up and vaporized. The rapidly 80 swirling air within the mixing chamber will quickly vaporize whatever portion of the gasoline may find its way to the blades of the suction wheel. It is also manifest that the gasoline vapors and the air will be thoroughly intermingled in the mixing chamber before being delivered to the engine intake. The suction wheel will materially assist the suction from the engine in drawing air 85 through the carbureting chamber and delivering it to the engine intake, thereby insuring an abundant supply of fresh mixture to the engine and relieving the engine of the work of drawing air through the carbureting chamber. By this means the mixture is 90 practically delivered to the engine intake so that the instant the intake or inlet valves of the engine are opened a full charge of mixture is delivered to said valves.

Having thus fully described my invention, what I claim as new and desire to secure by Letters Patent, is:

1. A carbureter comprising a carbureting chamber, means for supplying gasoline thereto, an air inlet into said carbureting chamber, a pervious closure for the air inlet, means for moving said closure to place the carbureting chamber more or less in free open communication with the atmosphere.

2. A carbureter comprising a vertically arranged carbureting chamber having an air inlet at its lower end, means for supplying gasoline to the upper end of said carbureting chamber, a pervious, absorbent closure for the air inlet of said carbureting chamber and arranged to receive gasoline delivered into said carbureting chamber, means for vertically moving said closure, means whereby the said carbureting chamber may be placed in more or less open communication with the atmosphere by said vertical movement of said closure device, and means for drawing air through said absorbent closure and through the carbureting chamber.

3. A carbureter comprising a vertically arranged carbureting chamber having an air inlet at its lower end, means for supplying gasoline to the upper end of said carbureting chamber, an absorbent closure for the said air inlet, means for moving said

closure to place the carbureting chamber in more or less open communication with the atmosphere, and means for drawing air through said absorbent closure and through 5 the carbureting chamber.

4. A carbureter comprising a vertically arranged carbureting chamber having an air inlet at its lower end, means for supplying gasolene to the upper end of said carbureting chamber, an absorbent closure for the air inlet, means for vertically moving said closure, means whereby the said carbureting chamber may be placed in more or less open communication with the atmosphere by said 10 vertical movement of said closure device, and means for drawing air through said absorbent closure and through the carbureting chamber.

5. A carbureter comprising a carbureting chamber having an air inlet at its lower end, the lower edge of said chamber being in part oblique to the axis of the chamber, a previous closure device fitting said chamber, means for moving said closure device inwardly or outwardly beyond points on the 20 lower edge of the carbureting chamber to place said chamber more or less in open

communication with the atmosphere, means for supplying gasolene to said chamber, and means for drawing the carbureted air 30 through the carbureting chamber.

6. The combination of a carbureter comprising a carbureting chamber having an air inlet, means for supplying gasolene to said chamber, a previous closure for said inlet, 35 an engine intake connected to the carbureting chamber, a throttle valve in said intake, connections between said throttle valve and said previous closure for the inlet for operating said previous closure upon movement of said throttle valve, means for placing the carbureting chamber more or less in open communication with the atmosphere by said movement of the closure, and means in said connections for permitting the movement of said throttle valve without placing the carbureting chamber in open communication with the atmosphere. 40

In testimony whereof I hereunto affix my signature in the presence of two witnesses. 50
